United States Patent Office.

P. W. THOMAS, OF WATERBURY, VERMONT.

Letters Patent No. 91,053, dated June 8, 1869.

SAD-IRON HEATER.

The Schedule referred to in these Letters Patent and making part of the same.

To all whom it may concern:

Be it known that I, P. W. THOMAS, of Waterbury, in the county of Washington, and State of Vermont, have invented certain new and useful Improvements in Sad-Iron Heaters; and I do hereby declare that the following is a full, clear, and exact description thereof, reference being had to the accompanying drawings, and to the letters of reference marked thereon, which form a part of this specification, and in which—

Figure 1 represents a side view, and

Figure 2, a plan view of my sad-iron heater.

Similar letters indicate like parts in both figures.

My invention relates to improvements in sad-irons, and to this end, in providing the heater with sliding doors and movable slats, for the purpose of fitting any sized sad-iron handle.

To enable others skilled in the art to which my invention appertains, to make and use the same, I will now describe its construction and operation.

In the accompanying drawings—

A represents the heater, made of iron, or any suitable material, and opened at the bottom, with a centre-piece, B, on top, said piece being provided with notches *a a' a'* upon its edges to receive the handles of the irons.

b b represent slides, formed with a notch *b'*, working over the notches *a' a'*, as seen in fig. 2.

C C represent doors sliding in grooves formed in the upper edges of heater A.

d is the handle of the heater, and *e e*, the handles of the sliding doors *C C*.

D represents the sad-iron in position for heating.

The operation of my heater is as follows:

The irons are first placed and secured in the heater by placing one end of the handle in notch *a*, and the other end in the long notch *a'*, and the slide *b* slid against the said end. The doors *C C* are then closed, and the heater placed upon the stove, or any suitable place for heating the irons.

It will be seen that by this arrangement of notches and slides, the heater can be used for any-sized sad-iron.

Having thus described my invention,

What I claim as new, and desire to secure by Letters Patent, is—

1. The notched slides *b b*, in combination with the top *B*, provided at its edges with notches *a a' a'*, substantially in the manner and for the purpose set forth.

2. In combination with the above, the sliding doors *C C*, substantially as described.

In testimony that I claim the foregoing as my own, I affix my signature in presence of two witnesses.

P. W. THOMAS.
